CLAIM

The ornamental design for a “bottle display kiosk”, as shown and described.

DESCRIPTION

FIG. 1 is a first front perspective view of the bottle display kiosk, showing my new design;

FIG. 2 is a second front perspective view thereof;

FIG. 3 is a front elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear elevational view thereof;

FIG. 9 is a rear perspective view thereof;

FIG. 10 is a second rear perspective view thereof;

FIG. 11 is a front exploded perspective view, showing a removable display portion thereof;

FIG. 12 is a second front exploded perspective view of FIG. 11;

FIG. 13 is a front exploded view of FIG. 11;

FIG. 14 is a left side exploded view of FIG. 11;

FIG. 15 is a right side exploded view of FIG. 11;

FIG. 16 is a top plan exploded view of FIG. 11;

FIG. 17 is a bottom plan view of FIG. 11;

FIG. 18 is a rear exploded view of FIG. 11;

FIG. 19 is a rear exploded perspective view of FIG. 11; and,

FIG. 20 is a second rear exploded perspective view of FIG. 11.

The broken line showing of the environment is illustrative of preferred component alignments only and forms no part of the claimed design.

UNITED STATES PATENT AND TRADEMARK OFFICE
CERTIFICATE OF CORRECTION

PATENT NO. : Des. 584,537 S
APPLICATION NO. : 29/293371
DATED : January 13, 2009
INVENTOR(S) : Lawrence A. Cuzzocrea

Page 1 of 1

It is certified that error appears in the above-identified patent and that said Letters Patent is hereby corrected as shown below:

On the Title Page,

In the last paragraph of the description, cancel the text "The broken line showing of the environment is illustrative of preferred component alignments only and forms no part of the claimed design."

Signed and Sealed this

Twenty-fifth Day of August, 2009

David J. Kappos
